Filed Aug. 24, 1965, Ser. No. 482,059
2 Claims. (Cl. 114—125)

ABSTRACT OF THE DISCLOSURE

A bulk carrier vessel having a passive free surface tank stabilizer formed by the existing ship structure and comprising a pair of wing tanks located just beneath the main deck along the upper outboard sides of the hull and being elongated in the longitudinal direction and each having an inboard side formed by a downward and outward extending plate which serves to house tank liquid and reinforce the main deck. A perforated bulkhead is provided in each wing tank and arranged in the athwartship direction to minimize the fore and aft swash of the tank liquid. Existing girder plates project upward and outward from a bottom plate mounted on top of a corrugated bulkhead to transmit supporting forces to the main deck and serve as an interconnecting channel with a truncated profile for the wing tanks. The wing tank fore and aft dimension is greater than the channel so as to form a C-shaped tank. An aperture plate is secured to the boundary of the channel and wing tank and slopes downward and outward from the top of the tank and provides hydrodynamic damping for the liquid body which partially fills the tank.

The present invention provides a ship stabilizer and more particularly a stabilizer made mostly of existing ship structure such as the deck and supporting girder plates conventionally found in bulk cargo ships and the like.

The use of water tanks for the purpose of roll stabilizing a vessel dates back to the early 1900's and Frahm's early contribution to the art. See U.S. Patent No. 970,368. However, the industry did not consider the use of water tanks commercially feasible until the recent development of the flume type stabilizer; see, for example, U.S. Patent No. 3,054,373. Now that roll stabilization systems are being widely used, there is a present need in the art to reduce the expense, weight and volume requirements thereof so that the stabilizers detract as little as possible from the cargo handling capabilities of the vessel without losing their stabilizing effectiveness.

One concept of reducing the space and weight needed for stabilizers is to use existing ship structure as the container and damping means for the liquid stabilizing medium. But to use existing ship members as part of the stabilization system creates stress problems which must be solved so that the strength and structural function of these members are not undermined. One such solution is disclosed in U.S. Patent No. 3,164,120, wherein the stabilization system for a liquid cargo tanker comprises the existing longitudinal and transverse structural bulkhead system which cooperates with a portion of the hull.

But the problem of using existing ship structure for the stabilization system in a bulk cargo vessel still exists. Therefore, it is a primary object of the present invention to provide a stabilization system for a bulk cargo vessel wherein said system comprises, at least in part, existing structural members normally found in vessels of this type.

It is another object of the present invention to use existing structural elements of a bulk cargo vessel as part of the stabilization system therefor, without undermining or detracting from the structural functions of these elements.

2

It is yet a further object of the present invention to provide a ship stabilizer which in part comprises the supporting deck girders normally found in bulk cargo vessels.

It is still a further object of the present invention to provide a plurality of stabilizing containers spaced throughout the length of the vessel.

Other and further objects of the present invention will become apparent with the following detailed description when taken in view of the appended drawings in which:

FIG. 1 is a side elevation of a vessel schematically illustrating the positions of the stabilizer tanks in relation to the holes, corrugated transverse bulkheads, and deck;

FIG. 2 is a side sectional view taken along line 2—2 of FIG. 1;

FIG. 3 is a side sectional view taken along line 3—3 of FIG. 1;

FIG. 4 is a developed fragmentary view of the restricting plate taken along line 4—4 of FIG. 2;

FIG. 5 is a sectional elevation view taken along line 5—5 of FIG. 3; and

FIG. 6 is a sectional elevation view of the wing tank taken along line 6—6 of FIG. 5.

Referring to the drawings in detail, there is illustrated in FIG. 1 a conventional bulk carrying cargo ship, generally indicated as 10, having a plurality of longitudinally spaced holds 12 separated by corrugated transverse bulkheads 14 and provided with a main or upper deck 16. A suitable number of longitudinal bulkheads 18 extend substantially throughout the length of the ship and divide holds 12 into a number of lateral compartments. Each hold 12 has one or more hatchways 20 through which bulk cargo material is loaded and unloaded. Sloping, elongated girder plates 22 are positioned across the hull, and each has one edge in supporting engagement with the underside of main deck 16 and its other edge rigidly mounted to the top of corrugated transverse bulkheads 14. Any suitable manner, such as welding and the like, can be used to secure these edges to deck 16 and the supporting structure. For increased structural support, the girder plates 22 and their associated deck portion form in cross section a rigid triangular structure, better seen in FIG. 5.

An elongated narrow plate 24 is mounted atop each corrugated bulkhead 14 and serves as a base or bottom to which the lower sides of plates 22 are secured.

In accordance with the present invention, a pair of wing tanks 30 are built in next to the hull just below deck 16 and serve as part of the stabilization system in cooperation with selected pairs of the girder plates 22. These girder plates form the sides of the crossover channel between wing tanks 30 as further described below.

Referring to FIGS. 2—6, each wing tank 30 has two liquid-tight bulkheads 32 and a sloping bottom plate 34 which has a vertical leg 36 and a horizontal leg 38 welded to deck 16 and the hull, respectively. A vertically mounted transverse web 40 is mounted in each wing tank with its edges entirely in contact with plate 34, a portion of the hull, and a portion of the main deck 16. Web 40 serves to add additional transverse rigidity to the ship.

As can be seen in FIGS. 2—5, the portion of plate 34 mounted across the area at which the space between girder plates 22 communicates with the respective wing tank 30 serves as a sloping restriction plate 42. A plurality of restrictions or cuts 44 is provided therein and these openings decrease in dimension and cross section as they approach the bottom of plate 42 so as to interfere as little as possible with the force distribution within plate 42. Plate 42 terminates in an upper vertical leg 46, the top of which is welded or otherwise secured to the underside of main deck 16, and openings 48 are provided therein to reduce weight and to enable a free passage of air in a manner described below. A swash bulkhead 50 is provided

in each wing tank, preferably near the center thereof in order to prevent local sway and to eliminate unwanted turbulence from the wing tank.

The operation of the present invention will now be described. It is readily understood that the sloping deck girders 22 function in their normal manner to give the required structural support to main deck 16, and that the space between girders 22 provides a connecting channel between the pair of transversely aligned wing tanks 30 located at opposite sides of the hull. Additional structural support and rigidity is afforded by transverse webs 40 and liquid-tight bulkheads 32. In addition, girders 22 and bulkheads 32, along with bottom plates 34, main deck 16 and the hull of vessel 10, define an elongated, enclosed liquid container or tank which, when filled with a body of liquid, serves as the passive stabilization system for vessel 10. As the ship 10 experiences roll in response to the action of the particular sea, the liquid within the stabilizer transfers from one side to the other in response to the roll, and the effective mass of the liquid shifts to impart a stabilization moment to the vessel. Restriction plates 42 provide the appropriate energy dissipation and liquid damping as the liquid transfers therethrough.

The air above the liquid surface transfers freely between the wing tanks 30 and the connecting channel through openings 46 or any uncovered cuts 44 in restricting plate 42. This transfer of liquid from one side of the stabilizer to the other continues as long as the vessel continues to roll.

Any suitable liquid such as fuel, bunker oil, sea water and the like can be used as the stabilizing medium within the stabilizer. The natural frequency of liquid oscillation within the stabilizer can be selected to match the particular conditions of the ship and sea by merely adjusting the height of the liquid within the stabilizer. To develop the proper moment magnitude, a predetermined plurality of stabilizers are built in into the vessel and can be partially filled with liquid to operate in the manner described.

Other and further modifications can be made to the present invention without departing from the spirit and scope thereof, and it should be understood that although only two stabilizer locations were shown, any number of stabilizers can be used in order to obtain the desired magnitude of stabilizing moment required for a particular vessel. It should further be understood that although the plan profile of the container is shown as being C-shaped (see FIG. 3), plan container profiles of Z-shape and H-shape are also within the scope of the present invention.

What is claimed is:

1. A bulk carrier vessel having a main deck and a hull, and a passive stabilizer tank extending across said hull, comprising a pair of wing tanks each located beneath said

main deck at an upper outboard side of the hull and having its inboard bottom wall formed by a downward and outward sloping plate having its top secured to the main deck under surface and its outboard edge secured to the respective hull side, said tank further including an interconnecting channel formed by a bottom plate extending the length of the tank, a pair of girder plates projecting upward and fore and aft respectively from said bottom plate and having their top edges secured to the under surface of said main deck so as to transmit supporting forces thereto, said girder plates extending athwartship and intersecting the inboard walls of the wing tank so that the interconnecting channel has a truncated profile in cross section, the fore and aft dimension of the interconnecting channel being less than the fore and aft dimensions of said wing tanks so as to form a C-shaped tank, each said plate forming inboard side of each wing tank defining a plurality of openings aligned with the profile of the interconnecting channel to permit substantial liquid passage into and out of the wing tanks during the roll cycle and to provide a suitable amount of damping thereto, said openings extending in zones from generally the bottom to the top of the tank for hydrodynamically damping the liquid passage but permitting a free transfer of air therethrough, and a swash bulkhead arranged transversely in each wing tank and provided with a plurality of openings so as to decrease the fore and aft swash movement of liquid therein during operation, and a body of liquid partially filling the tank so as to form an air space over all parts thereof in the interconnecting channel and the wing tank, the liquid level being such that the tank liquid oscillation is generally tuned to the ship's roll, said vessel further comprising a corrugated transverse bulkhead secured therein contributing to the primary support for the main deck and having its top supporting said bottom plate of said tank so as to counteract the loading forces through the girder plates.

2. A vessel as set forth in claim 1 wherein the plates forming the inboard sides of each wing tank comprise an inboard vertical section connected to the main deck and an outboard horizontal section connected to the hull.
